United States Patent Office

Des. 191,384
Patented Sept. 19, 1961

191,384

RADIANT HEATER

Jon W. Hauser, St. Charles Township, Kane County, Ill.,
assignor to McGraw-Edison Company, Elgin, Ill., a
corporation of Delaware

Filed Feb. 6, 1959, Ser. No. 54,481

Term of patent 14 years

(Cl. D81—10)

FIG. 1 is a perspective view showing the front and right side of a radiant heater embodying my new design, the rear thereof being plain; and

FIG. 2 is an elevation showing the left side thereof.

The dominant features of the design reside in the portions shown in full lines.

I claim:

The ornamental design for a radiant heater, substantially as shown and described.
